CLAIM

The ornamental design for a roller of a roll unit for use in flour milling machines, as shown and described.

DESCRIPTION

FIG. 1 is a top, front and left side perspective view on an enlarged roller of a roll unit for use in flour milling machines showing my new design;

FIG. 2 is a front elevational view thereof, the rear, top plan and bottom plan being an identical image;

FIG. 3 is a right side elevational view thereof; and,

FIG. 4 is a sectional view taken along line 4—4 in FIG. 2.
